MORRIS WOOL AND FRANK W. WOOL, OF BURLINGTON, VERMONT

FLASHING

Application filed June 25, 1930. Serial No. 463,735.

Our present invention relates to interlocking sheet metal flashing, such as used in the mortar courses in building constructions at various points to prevent descent of moisture through the walls, and has for its primary object to provide a joint between the sections or strips of the flashing which will effectively prevent the passage of moisture through the flashing, and which will retain its moisture-proof effectiveness even when bent to such an extent as to destroy the effectiveness of an ordinary joint.

A further object is the provision of a joint which may be readily assembled, which will be sufficiently rigid to easily and properly maintain the sections of flashing in the desired position and relationship while the mortar is placed over the same, and which will permit of readily bending external or exposed portions of the flashing, where necessary, without danger of disconnection of the engaged parts.

In the accompanying drawings which illustrates our invention and forms a part of this specification:

Figure 1 is a detail perspective view of the inter-engaging edge portions of a pair of flashing sections in detached relation.

Figure 2 is a side or edge view, showing the sections in engaged relation.

Figure 3 is a view partly in elevation and partly in section showing our use of the flashing in building construction necessitating the bending of an exposed side of the flashing.

Referring to these figures, and particularly to Figure 3, we have shown therein our improved sheet metal flashing generally at 10, in one of the mortar courses of a wall 11 along and above a roof 12. In this instance the roof covering 13 is shown with an upstanding edge 14 and the flashing 10 has an exposed portion at the inner side of the wall 11 bent downwardly as at 15 to overlap the upstanding portion 14 of the roof covering, so as to thus not only prevent the descent of moisture through the wall 11, but also the passage of moisture into the wall from the roof 12.

Flashing of the present type, commonly

formed of sheet metal, is laid in sections, often so carelessly joined at their contacting edges as to destroy the efficiency thereof and cause the relative displacement of the sections in the flooding or mortar over the same. The joint of our invention prevents this, and in carrying the same into effect, we provide one section 10^a as in Figures 1 and 2 with an offset substantially flat engaging lip 16 along its engaging edge. The other contacting section 10^b has an undercut groove 17 and a channel 18 opening therethrough into this groove to receive the lip 16 so that the latter may seat within the groove with its offset in the channel and forming a substantial lock so as to avoid relative displacement of the two sections when so joined. The groove 17 constitutes a perfect watershed since it is formed in the first instance by reversely bent portions 19 and 20 of the section 10^b at opposite sides of the groove, these reversely bent portions being in the spaced parallel relation plainly shown in Figures 1 and 2. The lip 16 of section 10^a seats beneath the reversely bent portion 19 and the reversely bent portion 20 terminates in a flat free edge 21 doubled back thereon and approximately coextensive with the section 10^b so that it is thus adapted by the inherent springiness of the metal to seat flatwise against the undersurface of the section 10^a adjacent to its offset, when the sections are joined in the manner above described, as plainly seen in Figure 2. This arrangement is obviously such that a complete watershed results so that the flashing is perfectly moisture-proof and the joint is in no danger of destruction in so far as its water-proof quality is concerned, by the bending of an exposed portion such as indicated at 15 in Figure 3. In fact upon the bending of such an exposed portion the joint is tightened rather than loosened, and is in no danger even in unskilled or careless hands.

It is furthermore obvious that with a joint such as proposed by our invention ready assembly is permitted, and effective bond with the mortar is provided for, and all danger of displacement of adjacent sections during the flooding of mortar thereover is obviated.

What is claimed is:

A flashing of sheet metal sectional construction of which one section has an offset continuing terminal edge forming a flat lip and an abrupt shoulder along the inner portion of said lip, and the other section has spaced parallel portions thereof along one edge bent back upon themselves and forming an undercut groove and a channel between them centrally of the groove whereby to receive the said lip through the channel and within one side of the groove with the shoulder positioned in the channel and the two sections in the same plane, one of said bent back portions at the same side of the groove frictionally engaging the lip to hold the latter within the groove, and the other bent back portion having a reversely and outwardly bent back flat free edge normally 20 approximately in the same plane with its respective section and forcibly contacting in flatwise relation against the undersurface of the flat section in the assembled position.

In testimony whereof we hereunto affix our
25 signatures.
